CHARLES F. BALL, OF MILWAUKEE, WISCONSIN, ASSIGNOR TO CHAIN BELT COMPANY, OF MILWAUKEE, WISCONSIN, A CORPORATION OF WISCONSIN

MIXING AND AGITATING MACHINE

Application filed February 9, 1929. Serial No. 338,775.

The present invention relates to machines for mixing concrete and other substances; and consists of the improvements to be hereinafter pointed out.

5 In the accompanying drawings:

Fig. 1 is a side elevation of a truck and concrete mixer mounted thereon embodying the present invention.

10 Fig. 2 is a vertical sectional view on the line II, II of Fig. 1.

Fig. 3 is a broken detail view, enlarged, representing in plan one of the adjustable mixing blades of the machine, and

15 Fig. 4 is a sectional view on the line IV—IV of Fig. 3.

Referring to the drawings 2 indicates a motor truck which, so far as the present invention is concerned, may be of any usual or preferred character. Upon the chassis 20 of this truck is supported a rotatable cylindrical tank 3, adapted to contain concrete. It is now quite common practice in the making of concrete for construction purposes to employ a central plant where the ingredients of the concrete are assembled and stored in large quantities and are mixed in machines of large capacity, and from which the mixed concrete is delivered and distributed to the various jobs where it is to be 25 used.

During the transit from the central mixing plant to the places of use the concrete is agitated or mixed to maintain it in proper condition for use and prevent its setting or becoming hard during the time of 35 transit. It is in connection with such a transit mixer that the present invention is represented, although the invention is not limited to use in connection with machines 40 of this character.

The rotatable tank 3 is represented as provided with openings 4 in its ends. In the arrangement shown the front opening is closed by a plate 5 or other suitable closure, 45 the rear opening being utilized both for the charging and the discharging of material which is delivered by the truck. To permit and facilitate such charging and discharging, the tank may be provided with an adjustable chute or spout of any desired or

approved construction. Such device is not represented in detail as it does not form a specific part of the present invention, but is merely diagrammatically represented at 6.

The tank is provided with means for rotating it, it being represented as provided with a central sprocket ring 7, through which power to rotate it is delivered from any suitable source, such as the motor of the truck, a separate motor, or other arrangement, as may be preferred. It is supported so as to be easily revolved on its longitudinal axis, as for instance, at its rear end upon rollers 8, stationarily supported upon the chassis of the truck, and at its front end upon rollers 9, carried by an equalizing bar pivotally supported, at 25, on the chassis frame. The tank is preferably provided with tracks 11 with which engage the supported rollers 9 and 10.

Within the tank are mounted a number of blades 12, arranged to be set at angles such that, as the tank is revolved the contents thereof will be agitated and mixed. Each blade is supported upon a shaft 13 supported in a bearing 24 secured to the tank, preferably to the exterior thereof. Secured to each shaft 13, and outside the tank 3, is a crank arm 14, through which the shaft and the mixing blade that it carries may be 20 turned to permit the blade to be set and secured at the desired angle.

The mixing blades are arranged in several sets or series, arranged in different transverse planes longitudinally of the tank. 85 The several crank arms 14 of each set of blades are connected by a ring 16 supported exteriorly of the tank. Each ring carries a set of pins 17 corresponding in number to the number of mixing blades of a set, and 90 these pins extend through slots 15 in the arms 14 and thus constitute the direct connecting means between the ring 16 and the crank arms. The rings are suitably supported and guided, they being represented 95 as formed with slots 18 through which extend guiding pins 19 projecting radially from the tank. It will be seen, particularly by reference to Figs. 3 and 4, that the mixing blades may be axially adjusted by rota- 100

tive movements imparted to the rings 16. When the blades are all inclined in one direction their action will be not only to agitate the material within the tank, but to force it toward one end thereof, as, for instance, toward the front, as when the tank is being loaded; but when the blades are adjusted to another inclined position, as represented in dotted lines Fig. 3, the action of the blades will be to move the material toward the other end of the tank, for instance toward the rear, such action taking place when the tank is to be discharged of material.

If the blades are adjusted to an intermediate position, as represented in full lines Fig. 3, the blades will serve to agitate the material, but have no tendency to move it either toward one end or the other. Various means may be employed to adjust the blades; for instance, as represented in the drawings, the adjusting rings 16 may be provided with short gear racks 20 with which engage gear wheels 21 supported exteriorly upon the tank 3. The exposed end 22 of each shaft carrying a gear wheel may be angular in shape to receive a detachable crank as 23 by which the wheel may be manually rotated and the ring with which the wheel engages adjusted. As shown in Fig. 1, each wheel 21 is represented as being in engagement with two adjacent rings 16, so as thus to be able to simultaneously adjust two sets of the mixing blades.

The present invention may be operated as follows: Supposing that a batch of concrete such as a tank 3 will carry is desired at a particular job of work, truck 2 goes to the central mixing plant where the tank it carries is filled. As soon as the filling operation begins the tank is set into rotation, the mixing blades 12 having first been adjusted to such angles as will cause the material delivered to the tank to be carried toward the front thereof and away from the filling opening at the rear. The tank being filled, the chute 6 will be turned to position to close the filling opening 4, or, if the chute 56 should not be of construction to permit this, then a separate closure may be used for this purpose until the time for the discharge of the tank arrives. During transit from the central mixing plant to the job the tank 55 may be maintained in rotation and the contents thereof agitated continuously. On reaching the job the rotation of the tank is stopped, the mixing blades are adjusted so that when the drum is again revolved they 60 will move the material toward the rear, the chute 6 is adjusted to discharge or delivery position, and the mechanism that rotates the drum is started into operation. The result will be that the drum will be quickly discharged of its load, and the material by

reason of the agitation to which it has been subjected since being loaded into the tank 3, will be found to be in suitable condition for immediate use.

It will be observed that the several sets of mixing blades are independently adjustable, permitting one set of blades to be adjusted to one angle and another to a different or even opposite angle. This may be of advantage in certain machines and under certain conditions. For instance, the sets of blades toward one end of the machine may be adjusted to force the material toward the center of the machine, while those at the opposite end may be set also to force it to the center machine; or again the blades may all be adjusted to deliver away from the center of the machine. These capabilities of the machine come within the purview of the invention and may be carried out by the mechanism shown or mechanical equivalents thereof.

The arrangement of the mixing or agitating blades in sets that are disposed circumferentially of the tank has decided advantages, as has been herein pointed out. However, the blades might be arranged in sets disposed longitudinally of the tank, rather than circumferentially thereof, in which case there would be provided means for simultaneously adjusting the blades of a series or set to change their working angles as might be required, and such an arrangement is contemplated as being within the present invention.

It is to be understood that the present invention is not to be limited to the specific showing thereof in the drawings hereof. Such drawings are largely diagrammatic in character. For instance, while the invention is represented as applied to a transit mixer for which it is especially well adapted, it will be understood that it may be equally well applied to a concrete mixing machine intended for the successive mixing of small batches of concrete at the job where it is to be used. Other means than those illustrated for adjusting the angular positions of the mixing blades may be employed, and are contemplated as coming within the scope of the present invention.

What is claimed is:

1. In a machine for mixing concrete and other substances, the combination of a rotatable tank for the material, agitating blade inside the tank and revolving with it, arranged in sets, and means by which the blades of a set may be simultaneously adjusted to a desired inclination.

2. In a machine for mixing concrete and other substances, the combination of a rotatable tank for the material, agitating blades inside the tank and revolving with it, arranged in sets, the blades of the different sets being in different transverse planes

- longitudinally of the tank, and means by which the blades of a set may be simultaneously adjusted to a desired inclination relative to the axis of revolution of the tank.
- 5 3. In a machine for mixing concrete and other substances the combination of a rotatable tank for the material, agitating blades inside the tank and rotatable with it, the blades being arranged in sets which are 10 in different transverse planes longitudinally of the cylinder, a ring for each set of blades located outside the cylinder and rotatable relative thereto to a limited extent, and connections between a ring and the blades of a 15 set whereby a rotative movement of the ring will change the angular positions of the blades.
4. In a machine for mixing concrete and other substances, the combination of a rotatable tank for the material, agitating blades inside the tank and revolving with it, each blade being supported upon a radial shaft, bearings carried by the tank in which the shafts of the blades are mounted and 20 rotatable, and means exterior to the tank for rotating the shafts and changing the angles of the blades within the tank.
5. In a machine for mixing concrete and other substances, the combination of a rotatable tank for the material, mixing blades inside the tank and revolving with it, each blade being supported upon a shaft that is radial to the tank, bearings carried by the tank in which the shafts of the blades are 30 mounted and rotatable, the shafts and bearings being arranged circumferentially of the tank whereby the blades are disposed in series in different planes longitudinally of the tank, and rings supported exteriorly of 35 the tank each arranged to rotate the shafts of a set and thus change the angular positions of the blades.
6. In a machine for mixing concrete and other substances the combination of a rotatable tank for the material, mixing blades inside the tank and revolving with it, each blade being supported upon a shaft that is radial to the tank, bearings carried by the tank in which the shafts of the blades are 40 mounted and rotatable, the shafts and bearings being arranged circumferentially of the tank whereby the blades are disposed in series in different planes longitudinally of the tank, crank arms carried by the shafts 45 at their outer ends, and rings supported exteriorly to the tank each arranged to rotate relative thereto to a limited extent and connected with the crank arms of one set of blade shafts.
- 50 60 7. The combination stated in claim 6 including also means by which the rings may be separately adjusted to change the angles of the agitating blades.
8. The combination of a motor truck, a 55 tank supported thereby so as to rotate about

a fixed axis, the tank being provided with an opening through which it may be charged and discharged, a series of agitating blades within the tank and revolving therewith, and means exterior to the tank by which the 70 angular disposition of the blades may be changed, whereby the blades may be set to force the material in the tank away from the opening while the material is agitated and toward the opening when the material is to 75 be discharged from the tank.

9. In a machine for mixing concrete and other substances, the combination of a rotatable receptacle for the material to be treated, blades located inside the receptacle for agitating the material when the receptacle is rotated, means located exterior to the receptacle for adjusting the inclination of the blades relative to the axis of revolution of the receptacle whereby upon revolution 80 of the receptacle the blades will cause agitation of the material and will also tend to move it longitudinally in one direction or the other accordingly as they are adjusted.

In testimony whereof I affix my signature. 90
